CHARLES LÉONARD ARMAND MAURICE LEBLANC, OF PARIS, FRANCE, ASSIGNOR TO
SOCIÉTÉ ANONYME POUR L'EXPLOITATION DES PROCÉDÉS MAURICE LEBLANC-
VICKERS, OF PARIS, FRANCE.

ELECTRIC VALVE.

Application filed December 16, 1920. Serial No. 431,221.

To all whom it may concern:

Be it known that I, CHARLES LÉONARD ARMAND MAURICE LEBLANC, a citizen of the Republic of France, residing at 1 Boulevard de Montmorency, Paris, Seine, France, have invented certain new and useful Improvements in Electric Valves; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to electric valves, and has for its object to provide an electric valve which serves for transforming continuous current into single or polyphase alternating currents of any frequency which may be varied as required.

It may also be used to transform alternating currents of a given frequency into alternating currents of any frequency which may likewise be varied at will.

The method of operation of the valve is based upon certain phenomena which have been observed by the applicants in connection, for example, with a three-electrode mercury vapour lamp, and to which further reference will be made later.

According to the invention the electric valve comprises a lamp with three electrodes, namely anode, grid and cathode, of which the cathode is maintained in a state of constant incandescence, the said lamp being filled with a gas or inert vapour instead of being entirely evacuated, so that the current may be transmitted from the anode to the cathode by means of the ions instead of being transmitted solely by the electrons emitted by the cathode, the grid being interposed between the anode and cathode as in the case of audions, the said valve being operated by insulating the grid or by rendering it negative with relation to the cathode, by means of a switch which is opened or closed, thereby permitting the passage of current or cutting off the latter.

In order that the invention may be clearly understood it will now be described with

reference to the accompanying drawings in which—

Fig. 1 shows a three-electrode mercury vapor lamp.

Fig. 2 shows the variation of the current flowing from anode to cathode in the lamp Fig. 1 when alternating current is used.

Fig. 3 represents the value of a wave current which can be used in the lamp in order to obtain the same results as with alternating current.

Fig. 4 shows an arrangement for converting an alternating current of a given frequency into a single-phase alternating current of any desired frequency.

Fig. 5 shows six curves for the current values in the different circuits of Fig. 4.

Fig. 6 represents an arrangement of transformers having two oppositely-wound secondaries.

Fig. 7 shows an arrangement for converting an alternating current of a given frequency into an alternating current of lower frequency by the use of the positive and negative half-waves of the standard alternating current.

Fig. 8 shows an oscillator for converting continuous current into single-phase alternating current of very high frequency.

Fig. 9 shows circuits for converting three-phase current of standard frequencies into polyphase alternating current whose frequencies can be varied at will.

Referring now to the drawings, a three-electrode mercury vapour lamp formed by a vertical vacuum tube A has an iron electrode B arranged at the top, the mercury cathode C being disposed at the bottom, while at the centre a grid D of iron or tungsten, for example, separates the tube in two parts.

At F, in the immediate vicinity of the cathode, an auxiliary anode is arranged through which a continuous current, which is never interrupted, flows in order to maintain the surface of the mercury in a state of incandescence when no current passes through the principal anode B. A small battery of accumulators G in conjunction with a self-induction coil E supplies the necessary current. Another battery I con-

nected between the cathode C and the grid D enables the latter to be rendered negative with relation to the cathode.

By means of a switch J the grid may be connected to or disconnected from the battery, as desired.

Whether the grid is disconnected or not, a current can only flow through the lamp by passing from the anode B to the cathode 10 C, as the mass of mercury can never operate as an anode.

If a source of electricity having a constant electromotive force which is greater than 14 volts, and which tends to cause a current 15 to flow from the anode B to the cathode is connected between these elements, it will be observed that:

1. If the switch J has previously been closed, the grid being negative in relation 20 to the cathode, the electromotive force may be raised considerably without any current flowing.

2. If the grid is disconnected, a current 25 passes through the lamp the intensity of which can be measured in amperes. If the grid circuit switch J is then closed, there passes through the circuit JI a shunt of the current flowing through the coil E in the direction anode to cathode. Along the shunt 30 circuit JI, the potential decreases in the direction of the current, as is well known. It follows that the grid D, located at the entrance of the shunt circuit JI, is of a higher potential than the end of said circuit, that is to say, the positive pole of the 35 battery I, the potential of which is approximately the same as that of the cathode C. The grid can, therefore, never become negative relatively to the cathode. The action is 40 as though the effect of the battery I were neutralized.

If the source of constant electromotive force is replaced by an alternating current supply, a current will flow, still in the same 45 direction, from the anode to the cathode as long as the grid is disconnected. This current is interrupted as soon as the switch J is closed.

The variations in the intensity i of the 50 current which flows from the anode to the cathode, as a function of the time t may be shown by means of a curve such as that in Figure 2. The short interruptions are determined by the alternations of the electromotive force. This last frequency may be 55 as high as desired.

The same results can also be obtained if the electromotive force is always in the same direction, but drops in value periodically 60 below 14 volts, as for example, when these variations can be represented as a function of the time by the curve shown in Fig. 3.

Finally, the action of the grid does not cause the lamp to be extinguished when a 65 difference of potential (at least 14 volts in

the case of mercury lamp) is maintained between the anode and the cathode, but it prevents the lamp from re-lighting when it is extinguished spontaneously.

In the two last cases if the frequency of 70 variation of the electromotive force is greater than that provided by the successive opening and closing of the switch J, the lamp operates similarly to a valve, allowing 75 the current to flow or arresting it as the switch J is opened or closed. This manipulation, apart from entailing very little work, also permits a very high resistance to be imparted to the circuit containing the battery I, and the energy which it will have to 80 supply, particularly when it is traversed by a current emanating from the anode B, is entirely negligible.

Assuming in the first place that an electromotive force having a frequency α is 85 available and that it is desired to produce a single-phase alternating current having a frequency β smaller than the first, recourse will be had to the arrangement shown in 90 Figure 4.

In this arrangement K is the core of a transformer; the latter is provided with two primary windings M and N having the same number of turns, but wound in opposite directions. There is only one secondary winding P which constitutes the source of single-phase alternating current having the frequency β . If a current of the same direction is allowed to flow through the circuits M and N in succession, the same effect is produced as when a current flows alternately in one direction and then in the other in 100 the same primary circuit.

In the circuits M N are provided the small condensers Q Q connected in shunt between 105 their ends. The use of the said condensers is to be explained as follows:

Considering the circuit M with reference to the lamp A, the circuit is supplied with an alternating current whose frequency is α and which is to be reduced to the lower frequency β ; the lamp arrests the negative waves of this current due to its rectifying power, and only allows the positive waves to pass, this action taking place only while the grid has a positive charge, or as usually stated, when the valve is open. The valve is in fact left open for $\frac{1}{2\beta}$ second, and 110 during this time the original current produces in the circuit M, $\frac{\alpha}{2\beta}$ positive waves, 115 as shown on curve II, Fig. 5.

The current thus flows $\frac{\alpha}{2\beta}$ times, and has 120 a zero value each time during $\frac{1}{2\alpha}$ second.

These great current variations will produce by induction various complex and dis- 125

turbing phenomena in the adjacent circuits N and P.

The current having the frequency of α is divided up between the winding M and the condenser Q; the latter becomes charged as the current flows, and then during the time

10 $\frac{1}{2\alpha}$ in which the current is at zero, the condenser discharges and supplies current to the lamp A, instead of producing a succession of separate half-waves separated by empty spaces as shown in curve II, Fig. 5, the effect will be a continuous undulated 15 curve lasting for the time $\frac{1}{2\beta}$ as shown in Fig. 5, curve IV.

The entrance points for the circuits M and N fed by the alternating current having the frequency α , are arranged in parallel and 20 communicate with one of the poles of the source of supply; their end points are individually connected to the anodes of two lamps similar to that shown in Figure 1, the cathodes of which are maintained in a state 25 of incandescence by the same battery of accumulators G. Finally the two batteries G and I are connected to the other pole of the source of supply.

A rotating commutator is arranged at R 30 having a number of segments mounted on a ring S. All those of odd number are connected to one another and with a slip-ring T^1 , while all those of even number are also connected to one another and to a slip-ring 35 T^2 . The odd number segments are insulated from the even number segments. Any form of motor may be employed to cause the commutator to rotate at the required speed.

A fixed contact p presses against the ring 40 S and is connected to the pole of the battery I which serves for charging the grids. Two other fixed contacts q^1 and q^2 press against the slip-rings T^1 and T^2 and connect them respectively to the grid of each lamp.

Under these conditions the two grids successively become negative (with relation to the cathodes) and disconnected, one of the grids becoming negative while the other is disconnected.

In Figure 5 six curves I, II, III . . . VI are shown. The curve I represents the variations in the electromotive force of the alternating current having the frequency α , as a function of the time, which is utilized for feeding the valve; the curve II shows the variations in the intensity i of the current which is distributed between the circuit M and its condenser; while the curve IV shows the current variations j for the portion of this current which traverses the circuit M and which is not neutralized by the reaction of the condenser. The curves III and V represent the corresponding current variations i^2 and j^2 in the circuit N. Finally, the curve VI shows, to another scale, the varia-

tions in the number of ampere turns (na) which the circuits M and N develop around the magnetic core of the transformer K. These last variations have a frequency β which is entirely dependent upon the speed 70 of the commutator.

An alternating current having the frequency β will therefore be developed in the secondary circuit P.

It should be noted that the alternating 75 current supply only furnishes energy during half the time when it flows in a given direction, as may be seen from the curve Fig. 2 and curves II and III, Fig. 5.

The source of alternating current may be 80 made to operate continuously by employing two groups of apparatus similar to that shown in Figure 4.

For this purpose it suffices to allow this current supply to flow through the primary 85 circuit U of a transformer V (Fig. 6) which has two secondary circuits X and Y with the same number of turns but wound in opposite directions in order to make use of the positive and negative waves of the alternating 90 current supply.

The terminals of the two secondary circuits XY will be connected at one end to the cathodes of the four lamps in the two groups, while those at the other end will be 95 connected to the primary circuits M, N of the transformer K for each group, as shown in Fig. 7.

Only currents of the same direction can 100 flow in these primary circuits M, N. During the half-periods of odd number, corresponding to the positive waves of the source of electromotive force for example, a current will flow through the secondary circuit X, and during the half-periods of even number, corresponding to the negative waves, a current will flow in the secondary circuit Y. The source of supply will thus be utilized during the whole time.

If the two groups of apparatus shown in 110 Figure 7 are taken, they may be made to produce currents having frequencies which are displaced by $\frac{1}{2}$ period.

For this purpose it is only necessary to 115 mount the two commutators for these groups S^1, T^1, T^2 and $S^{1'}, T^{1'}, T^{2'}$ on the same shaft in such a manner that the segments of the ring S are displaced by a half segment with relation to those of the ring S^1 . Under these 120 conditions the flux variations developed in the core of the transformers KK will be displaced by a $\frac{1}{2}$ period. If each of them has only one secondary circuit P, two-phase currents will be produced. It is a matter of 125 common knowledge that nothing is easier than to produce two-phase currents by means of two cores forming the seat of the flux variations which are displaced by one quarter period.

With the arrangement shown in Fig. 7 130

which is probably the most desirable embodiment of the invention it is possible however to transform a single-phase alternating-current having a frequency α into single or polyphase alternating currents with a lower frequency β , this latter frequency depending solely upon the speed of the commutator which only has to interrupt currents having an energy which is practically zero.

It is only on very rare occasions that an opportunity is presented of carrying out a transformation of this kind but it is of interest, in view of the fact that, by applying the principles involved, it is very easy to transform a high tension continuous current into a single-phase alternating current, a good efficiency being obtained, on the condition that its frequency is made very high by means of the arrangement shown in Fig. 8 and on combining it with the arrangement shown in Fig. 7.

A mercury vapour lamp b which requires no attention is connected in shunt in a circuit comprising:

1. A resonator consisting of a condenser c and a self-induction coil d tuned to produce the frequency α .
2. The primary circuit U of a transformer V which as in the case of that shown in Fig. 6 may have two secondary circuits X and Y .

A self-induction coil e capable of maintaining constant the intensity of the current which flows through it for the duration of the period

$$T = \frac{I}{\alpha}$$

is arranged in series in the continuous current circuit, adjoining the anode of the lamp. Finally, the available continuous current supply is connected between the cathode C of the lamp and the beginning of the coil e , so that it tends to cause current to pass from the anode to the cathode of the lamp.

The potential of the current must be sufficient to enable the lamp to light up. Then, if the energy stored up in the condenser at the moment of lighting up is greater than that which will be consumed in the circuit containing the resonator and the primary circuit U for the duration of

the period $\frac{1}{\alpha}$, the current will be neutralized in the lamp and the latter will be extinguished before the end of each period to be relighted by the continuous current supply at the beginning of the following period. The oscillations will therefore be sustained naturally.

This system which was described in the French Patents No. 333,387 of the 25th June 1903 and No. 333,516 of the 1st July 1903

of the Société Anonyme Westinghouse has frequently been employed in wireless telegraphy for producing sustained waves.

To enable the lamp to be relighted it is essential to employ high tension continuous current. The necessity for storing in the condenser a quantity of energy which is greater than that consumed during the period $\frac{1}{\alpha}$ tends to make the latter very

short, so that only currents of very high frequency are produced.

It is of advantage, however, to make the frequency α of short duration with relation to the frequency β for the currents it is desired to produce, and the continuous current which it will be necessary in practice to transform into alternating-currents will always have a very high tension.

In order, however, to transform a high tension continuous current serving for the long distance transmission of energy, into polyphase alternating-currents of the customary frequency which is variable at will and of any tension, this continuous current is first transformed into a single-phase alternating-current of very high frequency by means of the arrangement in Fig. 8, the transformer V of this system being the same as the transformer V for the arrangement shown in Fig. 7, which is connected as in this case to the valve system.

Another important problem is the following:

Given three phase currents at the customary frequency, 25 or 50 cycles, for example, it is desired to transform them into polyphase alternating-currents the frequency of which can be varied as desired but can attain a value equal to several hundred periods for the purpose of feeding an induction motor which has to run at a speed of several hundred revolutions per second.

This is the most complicated case. The alternating-currents at the customary frequency are first transformed into high tension continuous current by means of a mercury vapour rectifier. This continuous current is then transformed into single-phase alternating-current of very high frequency. Finally, the latter is transformed into high frequency currents which it is desired to produce. For this purpose recourse is had to the arrangement shown in Fig. 9.

The currents at the customary frequency feed the primary windings (1, 2, 3) of a step-up transformer. The transformed currents are rectified by means of a mercury vapour rectifier 4 which is assumed to have six anodes, two secondary windings being allotted to each core so as to enable the source of supply to work constantly, that is to say, to utilize the positive and negative waves of the current.

The continuous current supplied by the

rectifier feeds a device similar to that shown in Fig. 8 combined with the valve shown in Fig. 7 which produces the arrangement shown in Fig. 9 which merely amounts to 5 the superimposing of the preceding systems, like letters designating similar parts.

The four lamps of the arrangement shown in Fig. 7 have been replaced, however, by a single lamp provided with four anodes B 10 located at the top of four extensions closed by four grids but having only one cathode. Not only is this arrangement more simple but it is only necessary to maintain one single cathode in a state of incandescence so 15 that economy in working is obtained.

Even in the most complicated case, namely, for an arrangement carried out in accordance with that shown in Fig. 9 the material required is appreciably reduced and 20 the successive transformations are effected with a very high efficiency.

The rectifier 4 and the lamp b are traversed by currents having a tension of several thousand volts, in view of which the drop 25 of potential of 14 volts caused by the passage of the current through the lamps is negligible. Similarly, only high tension currents, of a thousand volts for example, will be obtained in the lamp with four, 30 anodes which serves as a valve.

As these lamps are only traversed by currents of low intensity they will be of small size. Finally, the transformer V through 35 which high frequency currents pass and the transformers KK through which currents having frequencies considerably greater than the customary frequencies flow, will be very small with regard to their output, and will have a high efficiency.

40 For the sake of simplicity it has been assumed that the current for the lamp, which serves as a valve and that for charging the grids, is furnished by accumulators. In practice these would be replaced by magneto 45 mounted on the commutator shaft. Finally, the latter may be replaced in certain instances by a small alternator.

With the arrangement shown in Fig. 1 a 50 valve is obtained which can open and close the circuit of an alternating-current of any frequency, which may be employed as a switch.

By coupling similar valves and manipulating them successively in a predetermined 55 order, a single-phase current having a very high frequency may be transformed into single or polyphase currents of any frequency which may be varied as desired but which are always less than the first, and of 60 any desired potential.

The high frequency alternating-current may be produced by means of an oscillator fed by high tension continuous current. Means are thus available for transforming 65 this continuous current into single or poly-

phase alternating currents of any frequency variable at will and of any potential.

Finally, this continuous current may be obtained by rectifying the alternating-currents of the customary frequency by means 70 of a rectifier. It is thus possible to transform these alternating-currents into currents of another frequency which can be varied as required.

It has been assumed in the preceding description that the incandescent cathode of the lamp serving as a valve, was formed by a mass of mercury and that the fluid filling the lamp was mercury vapour. This arrangement possesses the advantage that the 80 cathode does not wear away in the course of time, as it re-constructs itself. It can however be replaced by a metallic filament which is kept incandescent by the passage of current, and the mercury vapour may be 85 replaced by a fluid such as argon or neon, the molecules of which, when split up by the electrons emitted by the filament, supply the ions necessary for the flow of current. 90

What I claim is:—

1. A frequency changing device comprising a pair of partial vacuum tubes each containing an anode, a grid, a cathode and a fluid, whereby the current shall be transmitted by the ions, an auxiliary anode for maintaining the cathode constantly in an incandescent state, means for intermittently imparting to the said grid a constant negative potential, a transformer having a single secondary winding and a pair of equal and oppositely wound primary windings having a common terminal forming one connection with a periodic source of current, said cathodes being connected together and to the other side of said source, the other terminals of said primary windings being respectively connected to said anodes. 100

2. A frequency changing device comprising a pair of evacuated tubes each containing an anode, a grid and a cathode, a suitable vapor contained in each tube whereby the current shall be transported by the ions, an auxiliary arc for maintaining the cathode in an incandescent state, a commutator for intermittently impressing a negative potential of constant value upon said grids; and a transformer having a single secondary winding and a pair of equal and oppositely wound primary windings having a common terminal forming one connection with a periodic source of current, said cathodes being connected together and to the other side of said source, the other terminals of said primary windings being respectively 115 connected to said anodes. 120

3. A frequency changing device comprising a pair of evacuated tubes each containing an anode, a grid and a cathode, a suitable vapour contained in each tube, whereby 130

the current shall be transported by the ions, an auxiliary arc for maintaining the cathode in an incandescent state, means for alternately making and breaking the connection 5 of said grid with a source of constant potential which is negative with respect to the cathode and a transformer having a single secondary winding and a pair of equal and oppositely wound primary windings 10 having a common terminal forming one connection with a periodic source of current, said cathodes being connected together and to the other side of said source, the other terminals of said primary windings being 15 respectively connected to said anodes.

4. A frequency changing device comprising a pair of evacuated tubes each containing an anode, a grid and a cathode, a vapor contained in each tube whereby the current 20 shall be transported by the ions, means for maintaining each cathode in an incandescent state, means for intermittently imparting a negative potential of constant value to said grids and a transformer having a single 25 secondary winding and a pair of equal and oppositely wound primary windings having a common terminal forming one connection with a periodic source of current, said primary windings each having capacitance, said 30 cathodes being connected together and to the other side of said source, the other terminals of said primary windings being respectively connected to said anodes.

5. A frequency changing device comprising 35 a pair of evacuated tubes each containing an anode, a grid and a cathode, a vapor contained in each tube whereby the current shall be transported by the ions, an auxiliary arc for maintaining the cathode 40 in an incandescent state, means for intermittently imparting a negative potential of constant value to the grids; and a transformer having a single secondary winding and a pair of equal and oppositely wound 45 primary windings having a common terminal forming one connection with a periodic source of current, said primary windings each having a condenser connected in parallel therewith, said cathodes being connected together and to the other side of said 50 source, the other terminals of said primary windings being respectively connected to said anodes.

6. A frequency changing device comprising 55 a transformer having a pair of equal and oppositely wound primary windings, each shunted by a capacitance; means for applying a current, the frequency of which is to be changed, to said primary windings; 60 and rectifying means for alternately interrupting the current flow through said primary windings at any desired frequency, said transformer also having a secondary winding from which is obtained current at 65 the desired frequency.

7. A frequency and phase changing device comprising a transformer having a single primary winding adapted to be connected to a periodic source of single phase n cycle current, and a pair of equal and 70 oppositely wound secondary windings having a common terminal; a pair of transformers each having a single secondary winding and a pair of equal and oppositely wound primary windings, each pair of said 75 primary windings having a common terminal each of which is connected to one of the other terminals of the secondary windings of the first mentioned transformer; a plurality of partial vacuum tubes each comprising 80 an anode, a cathode and a grid, and containing a vapor whereby the current shall be transported by the ions, means for energizing said cathodes in a continuous manner, each vacuum tube serving to connect the common terminal of the first mentioned transformer to one of the remaining terminals of the primary windings of the second mentioned transformers; and means for successively interrupting the current flow 85 through said vapor containing tubes at one quarter phase intervals of a desired m cycle frequency, whereby two phase alternating current of m cycles may be obtained from the secondary windings of said second mentioned transformers.

8. A frequency and phase changing device comprising a transformer having a single primary winding adapted to be connected to a periodic source of single phase n cycle current, and a pair of equal and oppositely wound secondary windings having a common terminal; a pair of transformers each having a single secondary winding and a pair of equal and oppositely wound primary windings, each pair of said primary windings have a common terminal each of which is connected to one of the other terminals of the secondary winding of the first mentioned transformer; a plurality of partial vacuum tubes containing a vapor whereby the current shall be transported by the ions, each comprising an anode, a cathode and a grid, and means whereby an auxiliary arc is enabled to excite the cathode in a continuous manner, each of the said tubes serving to connect the common terminal of the first mentioned transformer to one of the remaining terminals of the primary windings of the second mentioned transformers; and means for successively interrupting the current flow through said tubes at one quarter phase intervals of a desired m cycle frequency, whereby two phase alternating current of m cycles may be obtained from the secondary windings of said second mentioned transformers.

9. A frequency and phase changing device comprising a transformer having a single primary winding adapted to be connect-

ed to a periodic source of single phase n cycle current, and a pair of equal and oppositely wound secondary windings having a common terminal; a pair of transformers 5 each having a single secondary winding and a pair of equal and oppositely wound primary windings, each pair of said primary windings having a common terminal, each of which is connected to one of the other terminals of the secondary winding of the first 10 mentioned transformer; a plurality of partial vacuum tubes each containing a vapor whereby the current shall be transported by the ions, an anode, a cathode, a grid, and 15 means for producing an auxiliary arc for constantly maintaining the cathode in the incandescent state, each of the said tubes

serving to connect the common terminal of the first mentioned transformer to one of the remaining terminals of the primary windings of the second mentioned transformers; and means for successively connecting and disconnecting said grids with a source of constant potential negative with respect to the cathodes of said tubes at one quarter 20 phase intervals of a desired m cycle frequency, whereby two phase alternating current of m cycles may be obtained from the secondary windings of said second mentioned transformers. 25

In testimony that I claim the foregoing as my invention, I have signed my name. 30

CHARLES LÉONARD ARMAND MAURICE LEBLANC.
